UNITED STATES PATENT OFFICE.

HERMAN H. RUBIN, OF NEW YORK, N. Y.

PENDING

ASSIST GRIP.

Application filed November 23, 1928. Serial No. 321,410.

The present invention relates to an appliance adapted to be used by an occupant of a passenger conveyance such as an automobile to assist in controlling and steady his movements within the vehicle especially when it is in motion. The device is secured to an interior wall thereof, one ordinarily being positioned at each end of the seats and in convenient position to be gripped by a person moving into or out of a seat. One object of my invention is to provide a holding device or grip of great durability and strength and which, while flexible, will retain its normal shape and pleasing appearance and will always remain in convenient operative position under varying conditions of use. One embodiment of my invention is illustrated in the drawings forming a part of this specification and in which

20 Figure 1 is a side view with portions broken away and partly in section; and

25 Figure 2, a fragmentary view partly in section of the lower or free end with outer portions of the completed device removed to show interiorly disposed portions partly in section.

30 Referring to the drawings, a device according to my invention comprises a bracket 1, a body portion and a grip portion 3. The bracket may be of any desired type but is preferably of the form illustrated and is equipped with a ring 4. The body portion consists of a plurality of twisted cords 2 or the like, the illustrated embodiment consisting of 35 four cords twisted upon each other to form a rope-like member. In assembling, the ropes or cords are flattened a suitable distance at one end, as by raveling, and the raveled portion is passed through the ring 4 and bent down against a normal twisted portion of the cords and securely held in said position by 40 means of a metallic binding ring 5 or the like. A ring 6 is pressed around the cords 2 close to their opposite or lower end so that 45 the strands of cord projecting beyond said ring will form a relatively stiff and unyielding abutment against which to position a suitable grip member as 3.

50 Where a grip member such as a pompon is to be attached to the cords, a retaining member is provided preferably in the form of a metallic yoke 7 of wire. The free ends 8 thereof interlock with a clamping device or ring 9, such as a staple with its ends bent inwardly and in overlapping relation to form 55 a ring or collar encircling the cord or support,

which is preferably of some yielding or compressible material as knitted or twisted fabric, rope or the like. While there are various operative arrangements of interconnection between the ends 8 of yoke 7 and the clamp or ring 9, in a preferred embodiment, said ends 8 pass through said ring and are then bent back upon themselves toward the lower end of the body or supporting member. For greater security, the ring or clamp 6 is fastened around the body to afford an abutment or stop adjacent and opposed to the bent back ends 8 of the yoke 7, so that, if the ring 9 should slip or yield under pull, the ring 6 is in position to oppose disengaging movement of the bent back ends. A molding or ferrule 10 of wood or other suitable material, conceals the end of the body and connecting devices associated therewith. As indicated in both figures, portions of the inner surface of ferrule 10 bear against the bent back or end portions 8 of yoke 7, thus retaining them securely in operative position. It will be obvious that the connecting means hereinabove described may be utilized to attach grips or ornamental terminal members other than pompons for like purposes.

55 The connection between the bracket 1 and the upper end of the cords is effectively concealed by means of a knitted covering 11 or the like, which is supplied chiefly for the purpose of improving the appearance of the device.

60 The appliance or assist grip thus far described would normally be flexible owing to the flexibility of the ropes or cords, but it is preferable to have a device of this character somewhat resilient in order that it may remain normally in extended position when not 65 positively flexed. For this purpose, I utilize an elongated spring member of any suitable character or material. A preferred form of spring consists of a closely coiled steel wire 12, although it is contemplated that 70 any other type of spring material such for example as celluloid, hard rubber, rawhide or other material may be employed. Whatever 75 the type of spring, it is shorter than the total length of the cords 2 and is conveniently inserted between the twists or coils of said cords after the device has been assembled as 80 thus far described. It is of course possible to remove the spring member by the reverse of the operation employed in inserting it so 85 that the spring is therefore renewable in case 90 it suffers injury or deterioration. When as- 95

sembled as described, the ends of the spring are not clamped or otherwise fixed so that it is free to move longitudinally in a limited range within the twists of the cords and therefore has some relative movement with respect thereto when the body portion is bent or distorted.

While I have described one effective mode of securing the grip member 3 to the support or cords 2, it is contemplated that my invention includes any manner of securing or affixing the grip member thereto.

In addition to the advantages hereinabove referred to in connection with the description of one form of my improved construction, there is the further advantage that my invention provides a relatively inexpensive product due chiefly to the saving of labor in connection with the fabrication of the body member or support, the ease with which the resilient or spring member may be inserted therein, and the simplicity of the connecting means between the grip 3 and the body or cords 2.

25 I claim as my invention:

1. An assist grip comprising a body portion of coiled flexible material, attaching means at one end thereof, a grip at the other end thereof, and a resilient member positioned within the coils of said body portion and free to move longitudinally with respect thereto.

2. An assist grip comprising a flexible body portion, attaching means at one end thereof, a grip at the other end thereof, and a spring within said flexible member and with its respective ends free to move longitudinally with respect to said attaching means and said grip.

3. An assist grip comprising a plurality of twisted cords forming a body portion, attaching means at one end thereof, a grip at the other end thereof, and a spring concealed and surrounded by said twisted cords and capable of endwise movement relatively thereto.

4. In combination, a terminal member, a

flexible support therefor, a clamp embracing said support, and a metallic connecting member having a portion engaging said terminal member and having its free ends interlocking with said clamp to retain said terminal member in engagement with an end of said support.

5. In combination, a pompon, a flexible support therefor, a ring embracing said support adjacent to one end, a second ring embracing said support and spaced from said first mentioned ring, and a metallic connecting member having a portion engaging said pompon and having its free ends cooperating with said rings to retain said pompon in engagement with an end of said support.

6. In combination, a pompon, a flexible support therefor, a ring embracing said support adjacent to one end, a second ring embracing said support and spaced from said first mentioned ring, and a metallic connecting member having a portion engaging said pompon and having its free ends interlocking with said second mentioned ring and cooperating with said first mentioned ring to retain said mass in engagement with an end of said support.

7. In combination, a pompon, a flexible support therefor, a ring embracing said support adjacent to one end, a metallic connecting member engaging said pompon and having its free ends interengaging with portions of said ring and a ferrule embracing said support and positioned to retain said ends in operative ring engaging position.

8. In combination, a pompon, a support therefor, a ring embracing said support, a yoke shaped connecting member positioned with a portion of its bight engaging the pompon and its free ends extending through said ring, said ends being bent back upon themselves.

In testimony whereof, I have signed my name to this specification this 21st day of November, 1928.

HERMAN H. RUBIN.

DISCLAIMER

1,703,321.—*Herman H. Rubin*, New York, N. Y. ASSIST GRIP. Patent dated February 26, 1929. Disclaimer filed May 18, 1931, by the patentee.

Hereby enters this disclaimer to that part of the claim in said specification and patent, which is in the following words, to wit:

“1. An assist grip comprising a body portion of coiled flexible material, attaching means at one end thereof, a grip at the other end thereof, and a resilient member positioned within the coils of said body portion and free to move longitudinally with respect thereto.

“2. An assist grip comprising a flexible body portion, attaching means at one end thereof, a grip at the other end thereof, and a spring within said flexible member and with its respective ends free to move longitudinally with respect to said attaching means and said grip.

“3. An assist grip comprising a plurality of twisted cords forming a body portion, attaching means at one end thereof, a grip at the other end thereof, and a spring concealed and surrounded by said twisted cords and capable of endwise movement relatively thereto.”
